UNITED STATES PATENT OFFICE.

WILLIAM COOKE, OF ORR LAKE, ASSIGNOR OF TWO-THIRDS TO JOHN T. LENNOX AND ARCHIBALD SIMPSON, OF BARRIE, ONTARIO, CANADA.

STEAM-BOILER.

SPECIFICATION forming part of Letters Patent No. 341,132, dated May 4, 1886.

Application filed January 22, 1886. Serial No. 129,361. (No model.)

To all whom it may concern:

Be it known that I, WILLIAM COOKE, of Orr Lake, in the county of Simcoe, in the Province of Ontario, Canada, miller, have invented an Improved Steam-Boiler, of which the following is a specification.

The object of the invention is to design a steam-boiler in which steam will be generated with the least possible consumption of fuel; and it consists, essentially, in placing over the furnace of the boiler a rectangular chamber containing a series of horizontal tubes having open ends to communicate with a water-space on each side of the chamber, and which is placed within an outer shell, between which and the inner chamber a suitable water-space is left. The outer shell is extended above the inner chamber, so as to leave a chamber above the latter for steam. The top of the tube-chamber is closed, and is provided with a suitable number of smoke-pipes to extend through the steam-chamber, so that the smoke and heated gases passing from the furnace below the tube-chamber pass through the latter, and thence through the pipes into the smoke-stack.

Figure 1 is a perspective view of my improved boiler with one detachable side removed. Fig. 2 is a sectional elevation of same.

A represents the furnace.

B is a rectangular chamber containing a series of horizontal tubes, C, and placed, as indicated, immediately over the furnace A, so that the smoke and heated gases from the furnace shall pass upwardly between all the tubes till it reaches the top row of the latter, thence through the smoke-pipes D into the smoke-box E, and thence into the smoke-stack F.

a is a water-space formed between the outer shell, G, and the shell of the tube-chamber B. This space extends down below the chamber B, and surrounds, as indicated, the furnace A. The top of the space a communicates with the steam-space H, which may be made any desirable size, as the experience of the engineer constructing the boiler may suggest. The tube-chamber B is suitably stayed to the outer shell, G. The sides of the shell G op-

posite to the ends of the tubes C are detachably connected, so that they may be readily removed for the purpose of permitting the tubes C to be cleaned.

In addition to securing the detachable sides I to the shell G by bolts b, I provide at suitable distances apart stay-rods d, which are each carried through a tube and the sides I opposite to each other, so as to brace the latter firmly together.

As the smoke-pipes D pass through the steam-space H, the steam contained therein is to a certain extent superheated, thereby insuring dry steam from my boiler.

By holding the water in a series of tubes suspended over the furnace and so arranged that the heated gases arising therefrom must, in passing out, surround the said tubes, I secure a boiler which will generate steam much more rapidly than an ordinary boiler, in which the smoke and heated gases pass through tubes surrounded by a large body of water.

Of course I do not confine myself to any particular size of boiler, and a boiler constructed in accordance with my invention may be used for house-heating purposes as well as for steam-engines.

I attach importance to the plurality of smoke-pipes D passing through the steam-space H and discharging into the smoke-box E, for by this construction the heating-surface is greatly increased. I also attach importance to the detachability of the sides I, whereby the tubes can readily be gotten at for the purpose of repairs or cleaning.

What I claim as my invention is—

The combination, with the shell G and the horizontal tubes B therein, of the detachable sides I, the bolts b, and the stay-rods d, passing through said tubes and sides, and bracing the latter, substantially as herein shown and described.

Toronto, December 29, 1885.

WILLIAM COOKE.

In presence of—

CHARLES C. BALDWIN,
JAMES E. MAYBEE.
